UNITED STATES PATENT OFFICE

165,654

UMBRELLA

Ferdinand Kramer, Port Chester, N. Y., assignor to Folding Products Manufacturing Corporation, Long Island City, N. Y., a corporation of
New York

Application July 11, 1951, Serial No. 15,824

Term of patent 14 years

(Cl. D88—3)

To all whom it may concern:

Be it known that I, Ferdinand Kramer, a citizen of the United States of America, and resident of Port Chester, county of Westchester, and State of New York, have invented a new, original, and ornamental Design for an Umbrella, of which the following is a specification, reference being had to the accompanying drawing, forming a part thereof, in which:

Fig. 1 is a top plan view of an umbrella embodying my design in open position;

Fig. 2 is a bottom view thereof;

Fig. 3 is a front view of the umbrella in closed
position;

Fig. 4 is a sectional view of the umbrella taken immediately to the left of the central hub of Fig. 2; and

Fig. 5 is a perspective view of the umbrella in open position.

I claim:

The ornamental design for an umbrella, as shown.

FERDINAND KRAMER.
